UNITED STATES PATENT OFFICE.

WILLIAM H. PRESTON, OF VALLEY JUNCTION, WISCONSIN, ASSIGNOR TO
PHILIP M. KNIPPENBERG, OF PORTAGE, WISCONSIN.

WRENCH.

SPECIFICATION forming part of Letters Patent No. 728,007, dated May 12, 1903.

Application filed September 20, 1902. Serial No. 124,180. (No model.)

To all whom it may concern:

Be it known that I, WILLIAM H. PRESTON, residing at Valley Junction, in the county of Monroe and State of Wisconsin, have invented 5 certain new and useful Improvements in Wrenches, of which the following is a specification.

This invention relates to improvements in that type of monkey-wrenches having a sliding jaw and means for clamping the sliding jaw to a locking position after the same has been adjusted upon the shank.

The object of my invention is to provide a wrench of this character having a sliding jaw 15 so constructed that the same can be quickly adjusted and held firmly in place while being used and in which the several parts constituting the instrument can be easily and economically made, conveniently manipulated, 20 and which will effectively serve for its intended purposes.

My invention comprehends certain novel structural detailed combinations of parts, involving a non-circular shank having the fixed 25 head-jaw and threaded on its opposite edges, a jaw held to slide freely upon the said shank, a feed nut or sleeve having an internal annular face equipped with oppositely-disposed threaded portions and intermediate oppositely-disposed unthreaded portions, whereby 30 when the nut is turned in one direction the unthreaded portions will register with the threaded edges of the shank and slide freely thereover, and when turned to another position its threaded portion will engage the 35 thread on the shank and serve to clamp the sliding jaw in a locked engagement with the object it engages, such nut or sleeve having an interlocked engagement with the sliding 40 jaw to move with it on the shank, it also having an annular external ratchet-face having coaction with the pawl carried upon the sliding jaw, adapted to automatically engage the said ratchet-face and hold the nut from reverse turn during the operation of clamping 45 the sliding jaw in place.

In the accompanying drawings, in which like numerals indicate like parts in all the figures, Figure 1 is a perspective view of my 50 improved monkey-wrench. Fig. 2 is a verti-

cal section of the same. Fig. 3 is a horizontal section showing the parts adjusted to allow for a free sliding adjustment of the movable jaw. Fig. 4 is a similar view showing the parts adjusted to hold the sliding jaw to 55 a locked position. Fig. 5 is a detail view of the sliding jaw. Fig. 6 is a similar view of the turn nut or sleeve. Fig. 7 is a detail view of the locking-pawl hereinafter referred to.

In its practical construction my improved 60 wrench comprises a shank 1, upon the upper end of which is integrally or otherwise fixedly secured a stationary jaw 2. The shank 1 has its opposite sides 1^b made flat and non-threaded, its opposite edges being rounded 65 on a circle corresponding with the internal annular surface of the nut or sleeve 3, presently referred to, and the said edges have threads 1^a, the reason for which will presently appear. 70

The sliding jaw 4 has the usual rectangular mortises 4^a 4^b and a clamping member 4^c, that oppose the jaw 2. The front edge of the sliding jaw has a pendent extension 4^d, the lower end of which terminates in an inturned lip 75 4^e and bifurcated fingers 4^f, that straddle the front edge of the shank and serve to guide the jaw 4 in its vertical adjustments upon the said shank, and the said extension 4^d is disposed away from the front edge of the shank, 80 so as to produce a slotway in which the nut or sleeve 3 turns, said nut 3 having a thickness equal that of the space between the bottom edge of the jaw 4 proper and the lip 4^e. The nut or sleeve 3 is made circular and has 85 an internal bore whose diameter is equal that of the major axis of the shank 1, and said bore has two diametrically oppositely disposed smooth unthreaded surfaces 3^a and two alternately-arranged threaded surfaces 3^b. 90 The outer or peripheral surface of the nut or sleeve 3 has an annular ratchet-rim 3^c, with which a pawl 5, spring-acted to its locking position, engages, said pawl having a tooth 5^a, so beveled as to permit the nut 3 being 95 screwed home and to hold it from return movement. The pawl 5 is fitted in the socket 4^g, formed on the front face of the jaw 4, said front face also having an elongated slot 4^b for the passage of the tooth 5^a. The lower end 100

of the pawl 5 extends below the pendent extension of the sliding jaw 4 and terminates in a finger-piece 5°.

From the foregoing description, taken in connection with the accompanying drawings, it is thought the advantages of my improved wrench will readily appear.

When it is desired to freely move the jaw 4 upon the shank, the nut 3 is turned to bring the unthreaded portion of its bore into register with the threaded edges of the shank, said nut being held in its position by the pawl 5. When thus adjusted, the jaw 4 can be quickly slid up to clamp against the work, after which by turning the nut 3 to the right to bring its threaded bore portions into mesh with the threaded edges of the shank the jaw 4 will be held securely clamped against the work and from back turn or loosening by the pawl 5, which engages the external ratchet-face of the said nut 3. To release the sliding jaw, it is only necessary to push out the pawl 5, so its tooth 5^a will become disengaged from the ratchet-rim of the nut 3, which then can be turned to bring the smooth bore-surface into register with the threaded edges of the shank, when it (the jaw 4) irrespective of the position of the pawl 5 can be slid up or down at will. By making the ratchet-face externally of the nut it also forms a roughened surface to facilitate the turning thereof.

I am aware that sliding-jaw wrenches have heretofore been provided having a shank provided with a threaded surface and a washer 35 or nut formed with a gear-face adapted to move into mesh with the threaded edges of the shank, and I therefore make no claim, broadly, to such construction. My invention differentiates from what has heretofore been 40 provided in this type of monkey-wrenches, so far as I know, in the peculiar construction of the nut or sleeve and its coöperation with the shank and the sliding jaw and particularly in the detailed construction thereof, in 45 which the peculiar arrangement of the hold-back pawl and the ratchet-surface of the nut form essential features.

Having thus described my invention, what I claim, and desire to secure by Letters Patent, is—

1. A monkey-wrench, comprising the usual fixed and sliding jaws, the latter having an inturned lip, a shank with two plain and two threaded portions, a nut having an external annular ratchet-face, a central bore having 55 two oppositely-threaded surfaces and two intermediate plain surfaces, the threaded surfaces being arranged to mesh with the threads of the shank, the said nut being held to turn between the bottom of the sliding jaw and the inturned lip member of the said sliding jaw, a spring-pawl carried by the sliding jaw adapted to engage the ratchet-face of the nut, all being arranged substantially as shown and described.

2. The hereinbefore - described improvements in monkey - wrenches comprising in combination; a shank having two flat sides and two screw-threaded edges, and a fixedly-held jaw; a sliding jaw, said sliding jaw having a pendent member formed with an inturned lip, said lip having bifurcated ends fitting over the front edge of the shank, the front face of the sliding jaw having a vertically-disposed socket and a slot, a circular 75 nut or sleeve adapted to turn with one edge between the bottom of the sliding jaw and its inturned lip, said nut having a central bore formed with two oppositely-disposed smooth surfaces and intermediate screw - threaded 80 surfaces, and having an outer annular ratchet-face, and a spring-pawl mounted in the socketed edge of the sliding jaw, said pawl having a tooth projected through the slot in the 85 said jaw to engage the ratchet-face of the nut, the lower end of the pawl being projected below the inturned lip of the sliding jaw and ending in a finger-piece, all being arranged substantially as shown and for the purposes described.

WILLIAM H. PRESTON.
